SIDEWALK-PAVEMENT DOOR.

1,086,461.

Specification of Letters Patent.

Patented Feb. 10, 1914.

Application filed February 10, 1913. Serial No. 747,415.

To all whom it may concern:

Be it known that we, FRANK O'BRIEN, HIRAM A. BEALL, CECIL A. CROOK, and OSCAR M. BORG, citizens of the United States 5 of America, residing at Spokane, in the county of Spokane and State of Washington, have invented certain new and useful Improvements in Sidewalk-Pavement Doors, of which the following is a specification.

10 This invention pertains to sidewalk pavement doors and has for its object to provide doors suitable for the treading surface of a pavement and such as will have upper surfaces that will not become slippery when 15 wet by rain or snow.

Sidewalk pavements along business streets of cities are commonly set with doors leading to vaults or passage ways and excavations beneath. A common type of door used 20 for this purpose is a steel door hinged to a sidewalk pavement. The steel doors become slippery when wet by rain or falling snow, making them dangerous for pedestrians to walk upon lest they slip and fall or strain 25 themselves.

To obviate the dangers mentioned is one of the objects of the invention as well as to provide a construction that will be light and economical.

30 We accomplish our purpose by the use of a light metal base with fibrous covering, the latter serving as the treading surface. The two elements being so connected and united and connected with the pavement or walk 35 as to provide suitable and safe passage for pedestrians over the same.

We find that we can provide a construction whereby the fibrous covering can be attached to the top surface of ordinary steel 40 doors already installed in a sidewalk pavement, as to substantially serve the purposes desired, as well as to manufacture the improved doors outright.

We have illustrated both methods mentioned in the accompanying drawings, in which —

Figure 1, is a top plan view of a pair of doors hinged to a fragmental pavement, one of the doors being an ordinary steel 50 door previously installed in the sidewalk pavement with the fibrous covering secured thereto, and the other one being a door originally manufactured according to the improved plan, Fig. 2, is a transverse sectional view taken on the line 2—2 of Fig. 1, Fig.

3, is an enlarged fragmental sectional view of the door first described in Fig. 1, Fig. 4, is an enlarged fragmental sectional view of the door last described in Fig. 1.

In the detail description of the parts following, wherein fiber or a fibrous covering is referred to, the same may be composed of a mixture of cotton or other vegetable or animal or mineral fiber, woven or connected together with cementitious matter composed of rubber, bituminous or other mineral or vegetable matter. In the illustration shown, whereby we apply the fibrous treading surface 10 to a steel door already installed in a sidewalk pavement 11, we have 60 provided a metal base 12 with an edge terminating in an upwardly and inwardly extending flange 13 giving a beveled outer surface 14 and providing a channel 15 into which the edge 16 of the fibrous substance 65 10 extends. This construction protects the edge 16 of the fibrous substance 10 and provides a suitable mounting edge for the door and a proper approach to or from the pavement 11. If thought desirable, the frame 70 17 supporting the hinges 18 may be sunk into the sidewalk pavement 11 sufficiently to bring the upper surface of the fibrous substance 10 to a position horizontal with the upper surface of the sidewalk pavement 11. 75 The metal base 12 and fibrous substance 10 should then be secured to the upper surface of the original door 19 by bolts or rivets 20 extending through the same as shown in Fig. 3. If desired, an eye or sleeve 21 may be 80 adjusted in an opening through the parts 10, 12 and 19 and the bolt or rivet 20 inserted in the same as shown in Fig. 3.

When the door is originally manufactured embodying the improvement, a suitable 95 metal base 22 is provided having an upwardly extending marginal portion 23 reaching to a point horizontal with the top surface of the fibrous filling 10 as shown in Fig. 4. The upturned marginal portion 23 100 furnishes a protection for the edge 24 of the fibrous filling 10 as well as furnishing a suitable marginal connection with the outer frame 17 to which the door is hinged and which the door is made to fit. The fibrous substance 10 and base 22 should be secured firmly together in horizontal alinement by some suitable means as by bolts or rivets 25 105 as shown in Fig. 2.

There may be added to the base 22 up- 110

wardly extending parallel strengthening ribs 26 between which and the marginal portions 23 the non-slip fibrous covering 10 may be secured with the upper surfaces of each 5 the covering 10, the marginal portion 23 and the ribs 26 on a horizontal plane.

What we claim is,

1. A sidewalk or pavement door structure comprising in combination, a door supporting frame, open door frames hinged to said supporting frame and each comprising a metallic or composite base, a fibrous covering thereto and means for rigidly uniting the two parts together and an upwardly extending marginal flange to said metallic or composite base extending around the same and reaching upwardly to a point horizontal with the upper surface of the fibrous portion. 10
- 15 2. A sidewalk or pavement door structure comprising in combination, a door supporting frame, open door frames hinged to said supporting frame and each comprising a metallic or composite base, an upwardly ex-

tending marginal flange to said metallic 25 base and parallel supporting ribs extending upwardly from said metallic or composite base to a point horizontal with the top of said marginal flange and connected therewith, together with a surface filling on said 30 metallic or composite base between said parallel ribs and between the same and the marginal flange to a point horizontal with the top of said parallel ribs and marginal flange, and composed of a fibrous substance 35 consisting of a mixture of cotton or other vegetable or animal or mineral fiber, woven or cemented together.

In testimony whereof we affix our signatures in presence of two witnesses.
